UNITED STATES PATENT OFFICE.

FREDERICK E. CARLSON, OF NEW BRITAIN, CONNECTICUT, ASSIGNOR TO LANDERS, FRARY & CLARK, OF NEW BRITAIN, CONNECTICUT, A CORPORATION OF CONNECTICUT.

BOTTLE-STOPPER.

1,191,277.

Specification of Letters Patent. Patented July 18, 1916.

Application filed September 2, 1914. Serial No. 859,784.

To all whom it may concern:

Be it known that I, FREDERICK E. CARLSON, a citizen of the United States, and a resident of New Britain, in the county of Hartford and State of Connecticut, have invented certain new and useful Improvements in Bottle-Stoppers, of which the following is a specification.

The object of this invention is to produce a device of the character described having features of novelty and advantage.

In the drawings—Figure 1 is a central vertical section; Fig. 2 a bottom view of the cap. Fig. 3 a detail view showing the relation of the cork to the base of the cap.

Referring to the drawings, *a* denotes the knob of the stopper, which may of course be of any desired form, shape, or ornamentation; *b* the base thereof preferably formed separately therefrom and of sheet metal and connected thereto in any desirable manner. This base is centrally apertured as at *c*, and threaded either by the formation of an eyelet or by soldering a nut in place, or in some other convenient manner. The base has V shaped slits, leaving pointed parts which may be bent down to form the prongs *d*. *e* is a cork which is driven onto these prongs against the underside of the base. The top of the cork is preferably flat and the base is slightly concaved, with the result that when the cork is secured in position by the screw *f*, the head of which is fitted into an aperture in the cork and has a bearing on a metal washer *g* engaging

with the threaded aperture *c*, the edge of the cork is drawn down hard against the base forming a tight joint, and the prongs hold the cork in position so that it cannot turn while it is being drawn down into position. The aperture in the cork may be filled in by a cork plug *h*.

This construction provides an inexpensive stopper, combining the cork plug with any kind of a handle, and insures a tight joint between the two parts.

I am aware that the various parts of the device may be modified in details without departing from the spirit of the invention as set forth in the appended claims.

I claim as my invention:

1. In a device of the character described, a base having its under surface concaved, a flat-ended stopper fitted against said concaved surface, means for clamping said stopper against said concaved surface, and means on said base engaging said stopper to prevent its relative rotation.

2. In an article of the character described, a concave base having a central threaded aperture, a stopper having a flat surface arranged against said concave base, the stopper being centrally apertured, and a screw passing through the aperture in the stopper and engaging the threaded aperture in the base to draw the two parts together.

FREDERICK E. CARLSON.
